SPINNING NOZZLES

Friedrich Hildebrandt, Kassel-Bettenhausen, Germany, assignor to Spinnfaser Aktiengesellschaft, Kassel-Bettenhausen, Germany

Application February 7, 1957, Serial No. 638,756

Claims priority, application Germany February 8, 1956

6 Claims. (Cl. 18—8)

This invention, in general, relates to spinning jets having a central opening therein.

Spinning with spinning jets or nozzles with a large number of holes reaches its limits at the point where the threads spun in the middle of the nozzle surface are no longer washed with an adequate amount of the spinning bath, and spinning defects due to deficiency of the spinning bath appear in the middle of the filament rope.

Attempts have been made to alleviate these difficulties in spinning with nozzles with a large number of holes in various ways. In round nozzles, for instance, sectors without holes have been left by ray-shaped arrangement of the holes of the nozzle. By way of these sectors, the spinning bath is supposed to penetrate to the middle of the nozzle surface and the middle of the filament rope. With numbers of holes exceeding 4,000 to 5,000, the ray-shaped drilling pattern no longer suffices to assure a perfect spinning.

In the latter instance, the desired result is better achieved with broad-jet nozzles with an elliptical surface, in which the short axis of the ellipse is as small as possible in relation to the long axis. As it is a transition between a circle and a straight line, the ellipse also makes it possible to arrange a large number of nozzle openings largely next to one another. Because of their lengthened form, nozzles of this sort require a special spinning head consisting of a flange and counter-flange with holding screws. The filament drawing-off devices must be adapted to conduct the wide-band-type rope so that a vertical drawing-off of the filaments from the surface of the nozzle is assured.

In this connection, the employment of ring-shaped spinning nozzles is considerably simpler; and these nozzles are also well suited as regards the accessibility of the spinning bath to all the threads. In these nozzles the spinning openings are arranged in concentric rows. A part of the bath liquid emerges in the middle of the nozzle, through a more or less large opening formed by the nozzle ring, so that the filament rope is washed with the spinning bath both inside and out.

The present invention makes use of all these advantages of the ring-shaped spinning nozzle, and presents, furthermore, a considerable improvement over them. Through its shape and the arrangement of the spinning openings, it takes effect on the shape of the thread even in the first moment as it emerges from the nozzle openings.

The invention consists of a ring-shaped nozzle, the inner wall having a portion which is conically tapered toward the central opening, and cylindrical spinning openings which are drilled diagonally in said tapered surface at an angle differing materially from 90°. At the surface of the nozzle, they have an approximately elliptical shape. The nozzle openings lie in concentric circles and can be grouped radially into sectors, so that passages between them remain free for the access of the spinning bath. Ring-shaped nozzles are especially effec-

2

tive with the surface conically tapered toward the middle and the spinning openings drilled substantially parallel to the axis of the nozzle.

The spinning openings arising from the diagonal drilling of the inclined nozzle surface at an angle differing materially from 90° bring about an asymmetrical viscose filament formation because, for a given filament cross section, the viscose emerging at the higher-situated part of each nozzle opening contacts the sulfuric acid spinning bath rising from underneath later than the viscose emerging at the lower-situated part of the opening. The structural differences in the fibers caused by this asymmetrical thread formation bring about a spiral crimping, similar to that of wool. Preferably, the acute angle between the surface through which the hole is drilled and the axis of the hole does not exceed 45°.

Furthermore, the spinning nozzle according to the invention is especially advantageous because the fresh spinning bath rising from underneath in the hollow body of the nozzle necessarily reaches all the nozzle holes before it runs off over the upper edge of the nozzle. The nozzle thus becomes, as it were, itself a spinning trough, in which—as in spinning in a tube—the thread formation takes place in an evenly flowing spinning bath.

A preferred embodiment of the invention is illustrated in the drawing wherein a diametric cross section of a ring-shaped nozzle is illustrated. The nozzle comprises a conical wall 10 tapering inwardly to a central opening 12 formed by an inwardly flanged cylindrical wall 14 with flange ring defining an opening 16. The nozzle has a flanged, cylindrical outer wall 18, which, together with the conical wall 10 and cylindrical wall 14, defines an annular space 20. The conical wall 10 is provided with extrusion apertures 22, which are disposed at an acute angle differing materially from 90° with reference to the surface of the wall 10. In the embodiment illustrated, which is one preferred form of the invention, the apertures are disposed substantially parallel to the axis of the nozzle. The angle between the apertures and the surface of the tapering wall 10 may be increased, if desired, to one more nearly approaching 90°.

The invention is hereby claimed as follows:

1. A spinning jet with a central opening therethrough defined by an inner peripheral wall, said inner wall being joined with an outer peripheral wall and defining therebetween a hollow, peripheral space, the inner wall having a portion tapering inwardly toward the middle of the nozzle with a plurality of apertures parallel with the jet axis in said tapering portion communicating with said space and disposed with the axes thereof at an acute angle not greater than about 45° with respect to the surface of said tapering portion.

2. A spinning jet with a central opening therethrough defined by an inner circular peripheral wall, said inner wall being joined with an outer circular peripheral wall and defining therebetween a hollow, annular space, the inner wall having a portion tapering inwardly toward the middle of the nozzle with a plurality of apertures parallel with the jet axis in said tapering portion communicating with said space and disposed at an acute angle not greater than about 45° with respect to the surface of said tapering portion.

3. In a viscose spinning jet with a central opening therethrough defined by an inner peripheral wall, said inner wall being joined with an outer peripheral wall and defining therebetween a hollow, annular space, the inner wall having a portion tapering inwardly toward the middle of the nozzle with a plurality of apertures parallel with the jet axis in said tapering portion communicating with said space, each disposed at an acute angle differing materially from 90° with respect to the surface of said

tapering portion sufficient to provide spirally crimped, spun viscose filaments.

4. A ring-shaped spinning jet with a central opening therethrough defined by an inner peripheral wall, said inner wall being joined with an outer peripheral wall and defining therebetween an annular space, the inner wall conically tapering toward the opening of said nozzle with a plurality of apertures parallel with the jet axis in said conical wall communicating with said space and disposed at an acute angle not greater than about 45° with respect to the surface of said conical wall.

5. A ring-shaped spinning jet with a central opening therethrough defined by an inner peripheral wall, said inner wall being joined with an outer peripheral wall and defining therebetween an annular space and including an inner wall conically tapering toward the opening of said nozzle; and a plurality of apertures parallel with the jet axis in said conical wall communicating with said space and disposed at an acute angle not greater than about 45° with respect to the surface of said conical wall.

6. A ring-shaped, viscose spinning jet with a central opening therethrough defined by an inner peripheral wall, said inner wall being joined with an outer peripheral wall and defining therebetween an annular space and including an inner wall conically tapering toward the opening of said nozzle; and a plurality of apertures parallel with the jet axis in said conical wall communicating with said space and disposed at an acute angle not greater than about 45° with respect to the surface of said conical wall and sufficient to provide spiral crimped, spun viscose filaments.
